Fig. 5. Technical drawing of a surgical instrument, likely a retractor or similar device. The drawing shows a handle assembly with various numbered components. Key features include a central horizontal bar (47) with a slot (48) for a blade, a curved support arm (10) with a hook (16), and a locking mechanism (13, 14) for the handle. The handle itself is marked with numbers 1, 5, 51, 52, 9, 10, 11, 12, 13, 14, 15, 16, 17, 18, 19, and 20. The drawing is a line sketch with some cross-hatching for shading.

UNITED STATES PATENT OFFICE.

RUSSELL M. SWITZER, OF CHICAGO, ILLINOIS, ASSIGNOR TO O. S. SWITZER & CO., OF CHICAGO, ILLINOIS, A COPARTNERSHIP CONSISTING OF MABEL C. SWITZER, MINNIE E. LEIGH, AND RUSSELL M. SWITZER.

COVER ATTACHMENT FOR RECEPTACLES.

Application filed November 15, 1923. Serial No. 674,918.

My invention belongs to that general class of devices known as receptacle attachments, and relates particularly to an improved attachment for securing the closure or cover 5 on a jar or other receptacle. The same is particularly adapted for glass and earthenware products or the like, and so connects or secures the cover or closure on the receptacle that it may be opened or closed at will.

10 The invention has among its objects the production of a device of the kind described that is simple, efficient, durable, compact, attractive, sanitary and satisfactory for use wherever found applicable.

15 It has among its further objects the production of a device of the kind described which may be readily attached to various types of receptacles and closures, as well as removed therefrom if desired.

20 Many other objects and advantages of the construction herein shown and described will be obvious to those skilled in the art from the disclosures herein given.

To this end my invention consists in the 25 novel construction, arrangement and combination of parts herein shown and described, and more particularly pointed out in the claims.

In the drawings, wherein like reference 30 characters indicate like or corresponding parts:

Fig. 1 is a view in elevation of one style or type of jar and cover with my attachment applied thereto;

35 Fig. 2 is a top plan view of the same;

Fig. 3 is a section taken substantially on line 3—3 of Fig. 2;

Fig. 4 is a section taken substantially on line 4—4 of Fig. 2, illustrating the cardholder;

Fig. 5 is an enlarged sectional view taken substantially on line 5—5 of Fig. 2;

Fig. 6 is a sectional view taken substantially on line 6—6 of Fig. 1;

45 Fig. 7 is a view in elevation of a portion of the attachment;

Fig. 8 is a view similar to Fig. 6, illustrating a slightly modified form of clamping member;

50 Fig. 9 is a sectional view taken substantially on line 9—9 of Fig. 8;

Fig. 10 is a view similar to Fig. 1, illustrating another form of the attachment;

Fig. 11 is a top plan view of the same;

Fig. 12 is a side elevation similar to Fig. 55 10, illustrating another form; and

Fig. 13 is a top plan view of the same.

Fig. 14 is a view in elevation of the latch member.

Referring to the drawings in which the 60 preferred embodiments of my invention are shown, 1 represents a jar or receptacle of suitable size, shape and material, and 2 is a cover or closure therefor, also of suitable size, shape and material. I have illustrated 65 a receptacle which may be termed bowl shaped, having a neck slightly reduced with a flange 4 at the mouth, the cover 2 being provided with a knob 3, also having a reduced neck about the knob. This general 70 type of bowl or jar and cover is made in various sizes and of different materials and in numerous shapes, all having some of the features mentioned more or less similar. My attachment is designed to so secure or 75 hinge the cover to the receptacle that it may be opened and be supported without removing the cover from the receptacle so that the same is not mislaid or misplaced or the various covers of adjacent jars interchanged. 80 This is particularly desirable where the various jars contain various products, as for example cookies, crackers, candies, pickles, cigars, tobacco, and various other products, and where it is not desirable that the covers be shifted from one jar to another or become intermixed. The same is not only particularly adapted for use in stores and the like, but is also suitable for home use.

In the attachment shown, there is provided a clamping member on the jar and a clamping member on the closure, the two being operatively connected or hinged together so that the cover may be turned back or opened.

As most clearly shown in Figs. 5 and 7, I provide a band 5 arranged to be clamped about the top of the jar, the free ends 8 of the same being connected together by a bolt 7 or the equivalent. This band may, if desired, be slightly flanged at the edges, as indicated at 9, so as to give some strength or rigidity and also permit the use of a lighter weight material. However, the band should not be so stiff that it cannot be applied to the jar, and I have found that in many cases it is desirable to omit the flanges. Where the band is to be clamped on a

straight jar, the flanges may be provided to hold a desired number of rubber, felt or like inserts as desired, which would have a tendency to prevent displacement of the band where the exterior of the jar is smooth or is irregular in shape.

The cover clamp 6 is provided with an extending part 10, which in the construction shown in Figs. 5, 6 and 7, is integral therewith. As shown, part 10, forming an arm, is flanged at the sides as indicated at 11, one flange being extended to form the band 6, the free end 12 being brought around and secured to the flanges 11 by a bolt 13 or equivalent means. I have shown the band part 6 as flanged, it being understood that this is a matter of preference, and that the flanges may be omitted if desired. Flanges may, if desired, be formed as indicated at 14—14, so as to overlie the flanges 11, as most clearly shown in Fig. 3. The opposite end of the arm 10 is formed with a loop 15 adapted to engage with the bolt or pin 7, the same being formed as indicated at 16 and thence extended as at 17 to form a stop and limit the opening of the cover and supporting the same in its open position. The part 17 should be so designed that when the jar is fully open, the center of gravity of the cover is beyond the pivotal bolt 7, so that the cover will stay open.

It may be mentioned that part 16 may be soldered, brazed, riveted, or otherwise secured to the adjacent part, although generally this is not necessary.

I have shown the arm 10 provided with a prong 18 adapted to engage the underside of the cover at the edge and more securely maintain the same against displacement. I have found, however, that while this is desirable perhaps in the case of a very heavy cover, it is not essential. I have also shown arm 10 provided with the turned up prongs 19, which serve as price ticket holders. The price card may be very conveniently inserted in the holder, thereby indicating the price or contents of the jar. As before mentioned, the flanges on the clamping member 6 and clamping member 5 may be omitted where preferred.

In Figs. 8 and 9, I have shown a slight modification of arm and clamping member 6. In this case 21 represents the end of the arm, while 22 represents a separable band, the ends 24 of which are secured to the arm by a bolt 23 or the equivalent. In this instance, the flanges 26 may be provided on the extending parts 24 so as to securely maintain the parts against displacement.

In Figs. 10 and 11, there is shown a slightly modified form of arm. In this case, the cover 2 is provided with a projecting portion 30 or the equivalent, and the arm 29 constructed of twisted wire or the like which is looped as at 31 to engage with the

part 30, the same being bent over and around the pin 7 and thence extended as at 33 to form a stop. The opposite end of the arm is formed with the forks 34 arranged to engage the knob. Obviously, the arm 29 may be looped around the knob if desired, that is, the ends of 34 extended to overlap or such equivalent construction provided.

In Figs. 12 and 13, cover 2 is provided with the projecting parts 36 and 37, and a bale 38 provided with the ends looped or bent at 39 around the part 37, the opposite side 41 being looped as indicated at 42 around the projection 36, the same being extended as at 43 and 44 similar to the construction shown in Fig. 10. The same may have a loop 40 large enough for the knob 3 to pass through, or it may be constructed so as to fit closely about the knob.

In Fig. 5, I have illustrated how a gasket or the like 46 may be inserted on the cover if desired. Generally, the same is not employed, but there may be instances where the same is desirable. If preferred, the cover may be so constructed that the gasket is substantially maintained in place by suitably forming the cover as indicated at 47.

I have illustrated in Figs. 1, 2, 5, and 14, how a simple form of latch or securing means may be provided for maintaining the closure tightly closed. The latch 50, as shown, may be of suitable size, shape and material and secured to the band 5 in any suitable manner. A very simple construction is to strike up the lugs 51 on band 5 and secure the latch thereto by means of a bolt or pin 52 or equivalent means for the purpose. A similar or equivalent latch may be provided on the types of receptacles shown in Figs. 10 and 12. The design of the latch itself may be varied to correspond with the particular design of the closure and receptacle, that shown being particularly simple and inexpensive. In some instances, particularly where the rubber or like gasket is employed, the latch is particularly desirable. It also enables a dealer to ship out filled jars securely locked or sealed, but of course in this instance if desired additional securing means may be employed, although in many cases it would be unnecessary.

With all of the constructions described, the cover may be opened or closed in a most convenient manner. It is always in place, and breakage is minimized. The device is adapted for various styles of jars, and may be made in various sizes. The attachment may be finished in the desired manner such as nickel plating, oxidizing, japanning, enamelling, or the like.

Having thus described my invention, it is obvious that various immaterial modifications may be made in the same without departing from the spirit of my invention;

hence I do not wish to be understood as limiting myself to the exact form, construction, arrangement and combination of parts herein shown and described or uses mentioned.

What I claim as new and desire to secure by Letters Patent is:

1. In combination, a ring adapted to be clamped about a bowl having a detachable cover with a knob, and an arm for holding said cover in place on said bowl and permitting the opening and closing of the same, said arm provided with a loop adjacent one edge to be secured to said ring and hinged relative thereto and extended in one direction therebeyond to provide a stop to engage the bowl when the cover is fully open and extended in the other direction and flanged at its sides, one of the flanges being formed into a loop to be clamped about the neck of said cover, prongs formed on said arm intermediate said last-mentioned loop and the hinge to provide a ticket-holder, and a latch hinged to said band and adapted to engage the cover.
2. In combination, a ring adapted to be clamped about a bowl having a detachable cover with a knob, and an arm for holding said cover in place on said bowl and permitting the opening and closing of the same, said arm provided with a loop adjacent one edge to be secured to said ring and hinged relative thereto and extended in one direction therebeyond to provide a stop to engage the bowl when the cover is fully open, said arm comprising a flange formed into a loop to be clamped about the cover, and prongs formed on said arm to provide a ticket-holder.
3. In combination, a ring adapted to be clamped about a bowl having a detachable cover, and an arm for holding said cover in place on said bowl and permitting the opening and closing of the same, said arm hinged to said ring and provided with a stop to engage the bowl when the cover is fully open, said arm being formed into a loop to be clamped about said cover, a prong formed on said arm and adapted to engage under the edge of the cover, and a latch hinged to said ring and adapted to engage the cover.
4. In combination, a ring adapted to be clamped about a bowl having a detachable cover, and an arm for holding said cover in place on said bowl and permitting the opening and closing of the same, said arm provided with a loop adjacent one edge to be secured to said ring and hinged relative thereto and extended in one direction therebeyond to provide a stop to engage the bowl when the cover is fully open, said arm comprising a flange formed into a loop to be clamped about the cover, and prongs formed on said arm to provide a ticket-holder.

In testimony whereof, I have hereunto signed my name.

RUSSELL M. SWITZER.
